DISPLAY FORM

Pierre Cherdakoff, University City, Mo.

Application August 4, 1941, Serial No. 405,368

3 Claims. (Cl. 223—75)

This invention relates generally to display forms and, more particularly, to a certain new and useful improvement in forms especially adapted for displaying ladies' hosiery.

My invention has for its primary objects the provision of a hosiery display form of so-called knock-down type, which is extremely simple, inexpensive, and durable in structure, which may be readily shipped or transported in a flat, compact package, which may be quickly, simply, and conveniently set up for display purposes and, when set up, will support and display a stocking in such a manner as will realistically simulate the appearance of the stocking upon the wearer's limb, and which is highly efficient in the performance of its stated functions.

And with the above and other objects in view, my invention resides in the novel features of form, construction, arrangement, and combination of parts presently described and pointed out in the claims.

In the accompanying drawing—

Figure 1 is a side elevational view, partly broken away and in section, of a hosiery display form constructed in accordance with and embodying my present invention;

Figure 2 is a front elevational view, partly broken away and in section, of the display form;

Figure 3 is a plan view of the top or cross-connecting member of the display form; and

Figure 4 is a fragmentary transverse sectional view of the display form taken approximately along the line 4—4, Figure 1.

Referring now in more detail and by reference characters to the drawing, which illustrates a preferred embodiment of my invention, the hosiery display form comprises a first or primary member A and a second or complementary member B both stamped, dyed, blanked, or otherwise constructed flatwise preferably of heavy card-board, fibreboard, or other suitable material.

The member A preferably integrally includes a foot-portion 1 contoured in flatwise simulation of or resemblance to a human foot, and extending upwardly from the foot-portion 1, is a front flat strip 2 and a rear flat strip 3 outlined also in simulation of or resemblance to the curvature and formation of a human leg. As best seen in Figure 1, the foot-simulating portion 1 is formed in spaced relation to its base or lower face with a so-called ankle-margin, and in such margin and approximately midway intermediate the front and rear strips 2, 3, the portion 1 is provided with a slot or recess 4, for a purpose presently appearing and all as best seen in Figure 1.

The member B includes a base-portion 5 longitudinal bifurcated or forked, as at 5', for dovetail interfitting endwise engagement with, and at right angles to, the member A at the ankle slot 4, and upstanding from the base-portion 5, are suitably elongated strips 6, 7, respectively conforming to the inner and outer side contours of the calf of a human leg, all as best seen in Figure 2.

Provided for detachable co-operation with the companion members A and B, is a top or cross-connecting member C provided with four suitably positioned and shaped apertures 8 for snug-fitting engagement with the upper ends of the strips 2, 3, 6, 7, and similarly provided for supporting the entire display form in upright position, is a base D having an arcuate slot 9 for grippingly engaging the toe-portion 1' of the member A, as best seen in Figure 1.

Ordinarily, the display form will be shipped in a flat, so-called knock-down package and may very readily be set up or assembled by interfitting the members A, B, and C, as shown in Figures 1 and 2, thereby providing what may well be described as a three-dimensional display form. A stocking is then readily slipped over the assembled form very much in the same manner as it would be put on the human limb. The foot-simulating or base-portion 1 of the member A is then inserted at its toe 1' into the base slot 9, tightly wedging, but not damaging, the foot-portion of the displayed stocking, and holding the entire display in upright, attention-compelling position.

The form fulfills in every respect the objects stated, and it should be understood that changes and modifications in the contour, construction, arrangement, and combination of the several parts of the display form may be made and substituted for those herein shown and described without departing from the nature and principle of my invention.

Having thus described my invention, what I claim and desire to secure by Letters Patent is:

1. A hosiery display form comprising a first flat skeleton member contoured and outlined to conform approximately to the sidewise silhouette of a human leg and foot and including, as a unit, a foot-portion and front and rear strips projecting upwardly from the foot-portion, said strips being disposed registrably in spaced relation in the same vertical plane and said member having an upwardly opening slot in its foot-portion intermediate said strips, a second flat skeleton member contoured and outlined to conform ap-

proximately to the frontwise silhouette of a human leg above the ankle and including, as a unit, a base-portion and side strips projecting upwardly from the base-portion, said strips being likewise disposed registrably in spaced relation in the same vertical plane and the second member having a downwardly opening slot in its base-portion and said members being adapted at said slotted foot and base portions for interfitting right-angular engagement one with the other in crossed display formation, and means engageable with said strips for retaining said members in crossed display formation.

2. A hosiery display form comprising a first flat skeleton member contoured and outlined to conform approximately to the sidewise silhouette of a human leg and foot and including, as a unit, a foot-portion and front and rear strips projecting upwardly from the foot-portion, said strips being disposed registrably in spaced relation in the same vertical plane and said member having an upwardly opening slot in its foot-portion intermediate said strips, a second flat skeleton member contoured and outlined to conform approximately to the frontwise silhouette of a human leg above the ankle and including, as a unit, a base-portion and side strips projecting upwardly from the base-portion, said strips being likewise disposed registrably in spaced relation in the same vertical plane and the second member having a downwardly opening slot in its base-portion and said members being adapted at said slotted foot and base portions for interfitting

right-angular engagement one with the other in crossed display formation, and an apertured ring-like member engageable with the strips at their upper ends for retaining said members in crossed display formation.

3. A hosiery display form comprising a first flat skeleton member contoured to conform approximately to the sidewise silhouette of a human leg and foot and integrally including a foot-portion and front and rear strips projecting upwardly from the foot-portion, said strips being disposed registrably in spaced relation in the same vertical plane and said member having an upwardly opening slot in its foot-portion intermediate said strips, a second flat skeleton member contoured to conform approximately to the frontwise silhouette of a human leg above the ankle and integrally including a downwardly bifurcated base-portion and side strips projecting upwardly from the base-portion, said strips being disposed registrably in spaced relation in the same vertical plane and said members being adapted for interfitting tongue-and-groove engagement at said bifurcated base and slotted foot-portions in crossed display formation, a ring apertured for interfitting engagement with the strips at their upper ends for retaining said members in crossed display formation, and base-forming means for detachably engaging the first member at its foot-portion for supporting the form in upright display position.

PIERRE CHERDAKOFF.
